UNITED STATES PATENT OFFICE.

CHARLES G. BURKHARDT, OF BUFFALO, NEW YORK.

ROLLER-MILL FOR GRINDING GRAIN.

SPECIFICATION forming part of Letters Patent No. 251,826, dated January 3, 1882.

Application filed January 17, 1881. (Model.)

To all whom it may concern:

Be it known that I, CHARLES G. BURKHARDT, of the city of Buffalo, in the county of Erie, State of New York, have invented a new and useful Improvement in Roller-Mills for Grinding Grain, of which the following is a full, clear, and exact description, reference being had to the accompanying drawings, making part of this specification.

10 My improvement applies to that class of mills in which the material—grain, &c.—is ground between rollers. In my improved mill the grain has positive feed to the rolls, and after passing between them falls on a reciprocating sieve, which separates the finer from the coarser material, each going to a separate conveyor for removal from the apparatus.

15 In the drawings, Figure 1 is an end elevation of the apparatus. Fig. 2 is a side elevation of adjustable boxes, and Fig. 3 is a vertical transverse section of same. Fig. 4 is a vertical section of upper box, and Fig. 5 is a horizontal transverse section of same. Fig. 6 is a vertical section of lower box, and Fig. 7 is a horizontal section of same. Fig. 8 is a vertical transverse section through the apparatus. Fig. 9 is an enlarged section of one side of the feed-hopper. Fig. 10 is a top view of shaker, and Fig. 11 is a side view of same. Fig. 12 is 20 an end view of the brush-stick, showing the adjusting device. Fig. 13 is a detail view of one end of the brush-stick, showing the adjusting device. Fig. 14 shows the apparatus one-half in side view and one-half in vertical section, the end portions of two rolls being shown in side view. Fig. 15 is an end view of the apparatus, showing the driving mechanism. Fig. 16 is a detail transverse section of part of the grinding-surface of the roll, showing the back 25 of the teeth curved in the arc of a circle; and Fig. 17 is a similar section, showing the back of the teeth curved in the arc of an ellipse, the cutting-edge of the tooth being at the point in the ellipse where the conjugate diameter of said supposed ellipse would touch its periphery. Fig. 18 is an enlarged view of one of the sieve-supporting rollers.

30 A A are duplicate feed-hoppers, each provided at the bottom with a feed-roller, B, whereby the grain is removed from the hopper and fed to the grinding mechanism in a well-known manner.

35 C is a slide arranged in the bottom opening of each hopper A, on the underside of the outer wall of the hopper, and made adjustable toward the feed-roller B to regulate the feed. The slide C is moved by a screw, c, attached to a lug, c', of the slide by means of its head and a jam-nut, and working in a threaded lug, c'', secured to the hopper A. By turning the 40 screw c in one or the other direction the slide C is raised or lowered and the feed accordingly increased or reduced. B is another slide arranged in the bottom opening of each feed-hopper A, on the upper side of the outer wall 45 thereof.

D' is a yoke attached to the under side of the slide D, and extending through a slot in the outer wall of the hopper.

E is an eccentric mounted upon a horizontal shaft, F, and engaging in the yoke D'.

50 F' is an arm mounted upon one end of the shaft F, the two arms F' being arranged upon the same side of the machine and connected by a bar, G, whereby both arms and eccentrics 55 are actuated, and both slides D raised or lowered simultaneously.

If desired, cog-segments and gear-racks may be substituted for the eccentrics E and yokes D'.

55 The slides D limit the maximum amount of 60 material which can escape from the feed-hoppers, and also serve to shut off the feed entirely, when required, and the slides C are each adjusted separately to regulate the feed from each hopper independent of the other.

65 H represents an inclined board or plate upon which the grain falls from each hopper, and whereby it is conducted between the grinding-rolls I I', which are arranged in two pairs, side by side, in the frame of the machine, the rolls 70 constituting one pair being arranged one above the other. The roll I of each pair runs at a greater peripheral speed than the roll I', the contiguous surfaces of the rolls moving in the same direction when the rolls are used for reducing grain; but they may rotate in opposite directions when the rolls are employed for shelling or hulling grain. The rolls I I' have their cylindrical surfaces provided with spiral ribs i, laid in the same direction on both rolls, so that 75 the contiguous ribs will cross each other and have a shearing action on the material. The ribs are composed of a flat abrupt side, i', and a curved side, i'', of less inclination. The abrupt

side is laid parallel with a radial line, $i^3 i^3$, drawn through the middle of the rib, and the curved side is formed by the arc of a circle of ellipse, the center of the circle lying in the line $i^4 i^5$, which is a continuation of the abrupt side i' of the rib, whereby the edge of the tooth is made approximately rectangular. This form of the ribs i is clearly shown in Figs. 16 and 17, and the direction in which the rolls rotate is illustrated in the same figures by arrows, the roll having the greater speed being indicated by two arrows. The ribs in the two rolls are reversed—that is, the flat side is the advance side in the fast roll and the reverse side in the slow roll—when the rolls are used for grinding, as shown in Fig. 16, but when the rolls are used for hulling the curved sides are the advance sides in both rolls, as shown in Fig. 17. From six to thirty-two ribs to a circumferential inch are cut into the rolls, according to the kind of work for which the rolls are used.

J represents two or more inclined sieves, upon which the ground material drops from the rolls $I I'$, and whereby the finer parts are separated from the coarser parts, the latter passing over the tail ends of the sieves into a trough in which a conveyer, P , is arranged, and the finer parts, which are sifted through, falling into a hopper, N , which is provided at its bottom with a conveyer, O . The sieves J have a shaking motion transversely to their inclination, whereby an effective separation of the finer from the coarser particles is effected and the clogging up of the meshes of the screens is prevented. The sieves J are actuated by eccentrics l , mounted on a shaft, L , and the ends of the sieves impinge against adjustable springs M , whereby a greater or less jarring action can be given to the sieves. The latter are supported on rollers j by means of angle-pieces j' , attached to the under sides of the sieve-frames. The rollers j turn in supports secured to cross-pieces j^2 , which are attached to the frame of the machine. By this means a rectilinear motion is imparted to the sieves at right angles to their inclination. The rollers j are preferably constructed with convex peripheries to allow the inclination of the sieves to be changed without impairing the bearing of the rollers upon the cross-bars j' .

If desired, the number of sieves may be increased to divide the ground material into grades of different fineness, and in this case a separate conveyer or discharge-spout may be provided for each grade.

Q represents brushes arranged underneath the lower rolls to detach the meal which may adhere to them. The brushes Q extend through slots n at both ends of the machine and rest with their ends upon set-screws Q' , whereby they are adjusted toward and from the rolls.

I^2 represents the shaft of the lower roll, and R the cylindrical journal-boxes in which this shaft turns. The boxes R turn in pillow-blocks S , which slide vertically between parallel guides T , formed with the frame of the machine. The journal-boxes R are constructed

at one or both ends with an eccentric flange, R' , which rests upon a bearing, N' , between the lower ends of the guides T . The flange R' is provided with pin-holes r' , for the insertion of a rod, whereby the journal-boxes R can be turned in the blocks S . By turning the journal-boxes in the blocks S the eccentric periphery of the flanges R' bears against the bearing or support N' and raises or lowers the block S between the guides T , whereby a rectilinear vertical adjustment is given to the block S and the journal-box R supported therein. The eccentric flanges R' are provided with set-screws r^2 , which bear against the outer side of the pillow-blocks S , and whereby the journal-boxes are secured in position after being adjusted.

U are cylindrical journal-boxes, in which the shaft I^3 of the upper roll turns. These boxes are arranged in pillow-blocks S' , which slide between the guides T , and which rest upon eccentrics V , pivoted between lugs s , formed on the upper side of the lower blocks, S . By turning the eccentrics V the upper rolls are raised or lowered with reference to the lower rolls. v are arms secured to the inner ends of the shafts of the eccentrics V on the inner sides of the side frames of the machine, and W is a rod, which connects the two arms v on the same side of the machine. The rods W are connected by a cross-bar, X , whereby both rods and the four eccentrics are actuated simultaneously. The upper rolls are retained in position after being adjusted by a set-screw bearing against each of the arms v , as shown in dotted lines in Fig. 1.

Y is a spring, which bears upon the upper block, S' , and which is preferably arranged to surround the cylindrical oil-cup Y' , which forms part of this block. The tension of the spring Y is regulated by a screw, Z , which works in a threaded housing, Z' , and bears upon a disk or follower fitted upon the upper end of the spring Y . These springs permit the upper rolls to rise when a hard substance passes between the rolls, thereby preventing injury to the dress. In order to allow either end of the upper roll to rise independent of the other end, the upper journal-boxes, U , are provided with spherical bearings in the blocks S' , as clearly shown in Figs. 3 and 5. As shown in Fig. 6, the lower pillow-block, S , is composed of two side pieces, S^3 , and an upper connecting-piece, S^4 , to the lower side of which the side pieces are secured by vertical bolts s^5 . The connecting-piece S^4 is constructed on its upper side with a depression, in which the eccentric V finds a seat or bearing.

b represents the driving-belt running over a driving-pulley below, which is not shown in the drawings, and thence over a pulley, b' , upon the shaft I^3 of the upper fast roll I . From the pulley b' the belt runs over the tightener-pulley d , and thence over the pulley e upon the shaft I^2 of the lower fast roll I , and thence to the driving-pulley beneath, which is not shown.

d' is a pulley cast with or secured to the

tightener-pulley, and having a smaller diameter than the pulley d . The pulley d' is connected by a belt, f , with a pulley, f' , secured to the shaft I^3 of the upper slow roll I' . The shaft of this roll carries on the other side of the machine a pulley, h , which is connected by a belt, k , with a pulley, m , upon the shaft of the lower slow roll I' , as represented by dotted lines in Fig. 15. The pulleys b' and e upon the shafts of the two fast rolls II are of equal diameter, to cause these rolls to rotate at equal speed; and the pulleys h and m upon the shafts of the slow rolls $I' I'$ are also equal in diameter.

15 The shafts of the feed-rolls B carry spur-wheels B' , which mesh together and are driven by a pinion, o , mounted upon a shaft, p . The latter carries a pulley, q , connected by a belt with a pulley upon either of the shafts I^3 . As 20 the latter revolve in opposite directions the pinion o would rotate in an improper direction if the driving-belt were changed from one shaft I^3 to the other. To prevent this the pinion-shaft p is supported in a hanger, r , which is pivoted at t , and which can be adjusted by a 25 set-screw, t' , passing through a curved slot, r^2 , in the hanger, in such manner that the pinion o can be engaged with either of the gear-wheels B' . By this means the latter can be rotated in 30 the proper direction from either shaft I^3 .

Although no special claim is made to various parts of the machine shown, described, and not claimed, their illustration and description are considered necessary to a proper understanding of the machine and its mode of operation.

I do not desire to claim the adjustable bracket on which the pinion is supported, which operates the feed-rollers, this being shown and described for the purpose of illustrating the feed mechanism more fully.

I claim as my invention—

1. The combination, with the feed-slides D , having yokes D' on their under sides, of eccentrics E , engaging in said yokes and mounted 45 each on a separate shaft, F , arranged underneath each feed-slide, arms F' , secured to the shafts F , and a rod, G , whereby the arms F' are connected, substantially as set forth.

2. The combination, with the pillow-block 50 S and guideways T , of a journal-box, R , capable of turning in the block S , and provided with an eccentric flange, R' , bearing against a support, N' , substantially as set forth.

3. The combination, with the rolls $I I'$, of 55 the pillow-blocks $S S'$, rectilinear guideways T , and the eccentrics V , interposed between the blocks $S S'$ for adjusting the distance between the rollers, substantially as set forth.

4. The combination, with the rolls $I I'$, of 60 the pillow-block $S S'$, having lugs s , guideways T , and eccentrics V , pivoted between the lugs s , substantially as set forth.

5. The combination, with the rolls $I I'$, of the 65 blocks $S S'$, guideways T , eccentrics V , provided with arms v , rods W , connecting arms v , and cross-bar X , substantially as set forth.

6. The combination, with the rolls $I I'$, of the 70 pillow-blocks $S S'$, guideways T , eccentrics V , interposed between the blocks $S S'$, and adjustable spring Z , bearing upon the upper block, S' , substantially as set forth.

7. The combination, with the journal-box R , of the pillow-block S , composed of two side portions, S^3 , and connecting-piece S^4 , to which 75 the side portions are secured, substantially as set forth.

CHARLES G. BURKHARDT.
